UNITED STATES PATENT OFFICE.

CHARLES W. THOMAS, OF ST. LOUIS, MISSOURI.

METHOD AND APPARATUS FOR MAKING ARTIFICIAL LIMBS OF FIBER.

1,379,884.

Specification of Letters Patent.

Patented May 31, 1921.

Application filed September 8, 1920. Serial No. 408,884.

To all whom it may concern:

Be it known that I, CHARLES W. THOMAS, a citizen of the United States of America, and a resident of St. Louis, Missouri, have 5 invented new and useful Improvements in Methods and Apparatus for Making Artificial Limbs of Fiber, which invention is fully set forth in the following specification.

This invention relates to improvements in 10 a method and an apparatus for making hollow artificial limbs of fiber. In one of the methods heretofore employed in the formation of such articles, a tubular section of fiber is first soaked until it is plastic, the 15 plastic material is then placed on a form shaped to the required contour of the limb, then a cord under strain or stress is spirally wound around the plastic tube to compress the material to the contour of the form. 20 The application of the cord under a winding stress, sufficient to compress the material has a drawing across or circumferential movement around the material as to cause the cord to cut into the soft material to such 25 an extent as to weaken the wall of the finished product. Furthermore, when the article is dried and the cord removed, the exterior surface of the article is found to be scarfed and ridged by the impress of the 30 cord and roughened by the circumferential drawing of the same. As the finished article must have a smooth exterior surface, the ridges and roughened surface must be either dressed down to give the required 35 finish, or a filling must be applied to cover the blemishes. This additional treatment not only increases the cost of manufacture, but the dressing down tends to weaken the finished article, and the filling-in increases 40 the weight without materially adding to the strength.

In the method of the present invention, 45 plastic flat fiber cut to the required pattern is wrapped around a mold or form shaped to the contour of the limb that is to be produced. This form is mounted in a supporting frame to rotate on its longitudinal axis and, while rotated, a flat band or tape is wound without deforming tension around 50 the fiber to hold the latter in place. This flat tape is applied, not by a drawing or straining action as in the former method, but by external pressure applied to the surface of the tape contacting with the fiber in 55 a direction radial to the longitudinal axis of the form. By the application of this ex-

ternal radial pressure, the plastic material is deformed only inwardly and not circumferentially as with the strained cord in the former method. Consequently, as the tape 60 is wound without deforming tension, there is no tendency of the tape to cut into the soft material by being dragged circumferentially around the same. Furthermore, the employment of the flat tape also lessens the 65 tendency to cut into the soft material. Also, by employing the flat tape with the edges of the adjacent coils abutting each other, a smooth exterior surface is given to the article that requires but little or no finishing treatment to eliminate rough places. 70

The present invention also has for its object the provision of an improved apparatus by means of which the foregoing method can be carried out. 75

In the drawings, in which similar reference characters designate corresponding parts,

Figure 1 is a front elevation of an improved apparatus to be employed in the 80 practice of the novel method for making hollow artificial limbs;

Fig. 2 is a section on the line 2—2 of Fig. 1;

Fig. 3 is a side elevation showing a modification of the apparatus; 85

Fig. 4 is a plan view of the same.

Referring to the drawings, the supporting frame comprises two uprights 1 connected by the two horizontal cross pieces 2. Between the upper ends of the uprights is displaceably mounted the collapsible form or mold 3 on which is shaped the artificial member 4. The form 3 is of the usual construction, being formed of longitudinal sections, an inner member of which is wedge-shaped to expand the form and is easily withdrawn to collapse the other members. The exterior surface of the form is shaped to the required contour of the limb. With 100 the form mounted in operative position, a square projection 5 at one end engages a similarly shaped socket 6 on the inner end of the shaft 7 journaled in one of the uprights 1. The other end of the form has a bearing in which is journaled the inner end of the holding-screw 8 threaded in the other upright 1 in line with the shaft 7. On the outer end of the screw is the hand-wheel 9 for turning the screw into and out of the 105 upright. With the screw turned inwardly and its inner end in engagement with the 110

bearing in the adjacent end of the form and the square projection 5 at the other end of the form in engagement with the socket 6, the form is held in operative position in the machine. By turning the screw 8 outwardly, the form can be readily displaced. The shaft 7 has on its outer end a gear 10 meshing with a pinion 11 on the crank-shaft 12 journaled in the adjacent upright 1. By turning the crank-shaft, the form can be rotated on its horizontal axis for a purpose that will be explained further on.

Extending horizontally across the upper part of the supporting frame is the threaded traveler 13 journaled at its ends in bearing blocks 14 secured to the frame. The traveler is held against longitudinal movement by heads 15 engaging the outer sides of the blocks 14. On one end of the traveler is the gear 16 meshing with the pinion 11 so that the traveler will be rotated simultaneously with the form. Extending across the lower part of the supporting frame is a guide-rod 17 parallel to the traveler and having its 25 ends seated in blocks 18 secured to the frame.

A carriage is mounted on the traveler and guide-rod to move across the supporting frame in a position radial to the horizontal axis of the form when the latter is in operative position. This carriage comprises two vertical members 19 held in spaced relation by the block 20 secured between their lower ends and the plate 21 attached to their upper ends. On the lower ends of the members 19 are the bearing blocks 22 through which passes the guide-rod 17 and on the upper ends of the members are the threaded blocks or nuts 23 engaging the traveler 13. As the latter is rotated through its engagement with the nuts 23, the carriage is moved across the supporting frame.

Vertically guided in the upper part of the carriage between the members 19 is the recessed slide-block 24 held in alinement by friction rolls 25 journaled on pins projecting from the opposite sides of the slide-block and engaging vertical slots in the members 19. In the recess of the slide-block is the coiled spring 26 resting at its lower end 50 on the upper end of the screw 27 passing through the block 20 and engaged by the nut 37 resting on said block. This spring, when compressed, tends to move the slide-block toward the form 3 when the latter is in operative position. In the upper end of the slide-block is journaled the roller 28 having its periphery formed of medium hard rubber to bear against the form 3. By turning the nut 37 to vertically adjust 55 the screw 27, the tension of the spring can be regulated and the pressure of the roller on the form adjusted to meet the requirements. The purpose of the roller is to compress the material on the form by forcing 60 against the same a metallic band or tape 29,

which also may be made of woven fabric in the form of a flat cord.

The operation of the apparatus is as follows:

The material of which the artificial limb 70 is composed is vegetable fiber commonly furnished for the purpose. A sheet of this material is cut to the required pattern and soaked in water until it becomes soft and pliable. It is then wrapped on the collapsible form 3 and the latter is mounted in the apparatus between the ends of the shaft 7 and the screw 8 and the parts are adjusted to hold the form in place. By turning the traveler 13, the carriage 19 is moved to the 80 right, as the apparatus is shown in Fig. 1, to position the presser roller 28 opposite the thicker end of the form. With the carriage so adjusted, an end of the metallic tape, which may be wound on a spool carried by 85 the operator, is passed through the opening between roller 28 and the slide-block 24, partly around the roller and onto the end of the form, and is temporarily secured thereto in any suitable manner, for instance, by a nail driven through the end of the tape and the fiber into the wood of the form. Then, by turning the crank-shaft 12, through the intervening gears, the form 3 and the traveler 13 are simultaneously rotated. As the form is rotated, the metallic tape is spirally wound on the same. The tension of the tape is only slight, sufficient to guide it properly, but not enough to deform the plastic material. The rotation of 90 the traveler, through the intervening mechanism, will move the presser roller 28 along the form with the roller pressing the tape against the plastic material. The radial pressure of the roller will force the fibrous material against the form and shape it to the contour of the same. The pressure of the roller can be regulated to meet different requirements by adjusting the tension of the spring 26 by turning the screw 27. The 95 material shaped by the pressure of the roller is held in place by the metallic tape. As the tape is wound onto the material, the operator manipulates the same so that it is wound without deforming tension smoothly 100 onto the material with the edges of the adjacent coils abutting each other so that, at the completion of the winding, the material is inclosed by a metallic casing with a comparatively smooth contacting wall. The deformation of the plastic fiber is accomplished solely by the pressure-roller 28 bearing on the material, as the tape is wound without deforming tension. When the entire 105 length of the tubular section is wound, the other end of the metallic tape is temporarily secured to the form. Should it be required, to obtain further compression of the material, the roller can be applied again and any slack that may be rolled into the tape 110

can be taken up by readjusting the temporary fastener. After the material has been shaped to the contour of the form and the metallic tape applied and secured, the form is removed from the machine and the material dried in any suitable manner. During the drying, the material is firmly held to the shaped contour by the metallic tape. After drying, the metallic tape is removed and the exterior surface of the article will be found to be extremely smooth, owing to the flat contact of the metallic tape with the edges of the adjacent coils abutting each other. The mold is removed from the shaped article by withdrawing the wedge-shaped inner section to permit collapse of the other sections.

It is to be observed that, in the application of the tape, there is no straining or drawing of the tape across the material to displace the same circumferentially; the displacement of the material is only in a radial direction through the application of the presser roller. Consequently, the surface of the article will not be cut into grooves or roughened, such as would be the case of a cord wound on the material with a drawing strain or stress to compress the material. In the use of the flat tape, wound without deforming tension on the form and pressure applied by the presser roller, the article will be given a smooth exterior surface, requiring but little or no subsequent finishing to eliminate rough places.

In the modification shown in Figs. 3 and 4, there is a vertical carriage 19^a and a horizontal carriage 19^b, both of the same being constructed as the carriage in the first instance. On the carriage 19^a is the presser roller 28^a and on the carriage 19^b the presser roller 28^b, both rollers and their adjuncts being of the same construction as the presser roller in the first instance. The purpose of the plural presser rollers in the modification is to provide sufficient application of pressure in a single operation of the machine. With but one roller, the application of pressure might be insufficient to displace the material to the required extent and repetition of the operation would be required. With the two rollers there would be a double application of pressure in a single operation of the machine.

In the modification, the traveler 13^b for propelling the horizontal traveler is driven by the sprocket chain 30 leading from the sprocket wheel 31 on the traveler 13^a driving the vertical carriage to the sprocket wheel 32 on said traveler 13^b. The traveler 13^a is rotated as in the first instance.

In the modification, the flat tape, instead of being wound on a spool to be carried in the hand of the operator as in the first instance, is coiled on a reel 33 mounted on the horizontal carriage 19^b, the tape or band

leads from the reel over the guide-roll 34, under the presser roller 28^b and onto the tubular section of plastic fiber carried by the form. As the carriages travel across the machine, the tape is fed off the reel and is spirally wound without deforming tension on the form to be pressed thereon by both presser rollers 28^a and 28^b. The presser roller 28^a is positioned slightly in advance of the roller 28^b so that the latter will follow the spiral track laid by the former. The rear end of the horizontal frame 19^b is carried by a roll 35 that slides on a cross-piece 36 of the frame.

What is claimed is:—

1. The method of making hollow artificial limbs of sheet fiber, consisting in shaping the sheet fiber to the required preliminary pattern, soaking the fiber until it becomes plastic, placing the plastic sheet fiber around a form, deforming the plastic fiber to the contour of the form by rolling pressure progressively applied to the material, and retaining the deformed fiber on the form until set by a band wound without deforming tension on the fiber in advance of the rolling pressure to be conformed thereby to the contour of the deformed material. 80

2. In apparatus for making hollow artificial limbs of plastic sheet fiber, a rotatable form to receive the plastic sheet fiber, a roller under pressure movable along the form to bear on the plastic sheet fiber to deform the material to the contour of the form as the latter rotates, and a band wound without deforming tension on the plastic fiber as the form rotates in advance of the roller to be pressed by said roller to follow the deformation of the fiber to hold the deformed material to the contour of the form until 100 it becomes set. 95

3. In apparatus for making hollow artificial limbs of plastic sheet fiber, a supporting frame, a rotatable form displaceably mounted in the frame to receive the plastic sheet fiber, a carriage movable on the frame parallel to the axis of rotation of the form, a spring-pressed roller carried by the carriage to bear on the plastic fiber to deform the material to the contour of the form as 110 the latter rotates and as the carriage travels across the frame, and a band wound without deforming tension on the plastic fiber as the form rotates in advance of the roller to be pressed by said roller to follow 120 the deformation of the fiber to hold the deformed material to the contour of the form until it becomes set. 115

4. In apparatus for making hollow artificial limbs of plastic sheet fiber, a supporting frame, a rotatable form displaceably mounted in the frame to receive the plastic sheet fiber, a carriage movable on the frame parallel to the axis of rotation of the form, a spring-pressed roller carried by the car- 125 130

riage to bear on the plastic fiber to deform the material to the contour of the form as the latter rotates and as the carriage travels across the frame, means for regulating the pressure of the roller, and a band wound without deforming tension on the plastic fiber as the form rotates in advance of the roller to be pressed by said roller to follow the deformation of the fiber to hold the deformed material to the contour of the form until it becomes set.

5. In apparatus for making hollow artificial limbs of plastic sheet fiber, a supporting frame, a rotatable form displaceably mounted in the frame to receive the plastic sheet fiber, a carriage movable on the frame parallel to the axis of the rotation of the form, a spring-pressed roller mounted on the carriage to move radially to the axis 60 of the form to bear on the plastic fiber to deform the material to the contour of the form as the latter rotates and as the carriage travels across the frame, and a band wound without deforming tension on the plastic fiber as the form rotates in advance of the roller to be pressed by said roller to follow the deformation of the fiber to hold the deformed material to the contour of the form until it becomes set.

15 6. In apparatus for making hollow artificial limbs of plastic sheet fiber, a supporting frame, a rotatable form displaceably mounted in the frame to receive the plastic sheet fiber, a carriage movable on the frame parallel to the axis of rotation of the form, a block slideable in the carriage at right angles to the axis of the form, a spring pressing the block toward the axis of the form, a roller carried by the slideable block and 75 pressed by the spring to bear on the plastic fiber to deform the material to the contour of the form as the latter rotates and as the carriage moves across the frame, means for regulating the tension of the spring to 80 adjust the pressure of the roller, and a band wound without deforming tension on the plastic fiber as the form rotates in advance of the roller to be pressed by said roller to follow the deformation of the fiber to hold the deformed material to the contour of the form until it becomes set.

20 7. In apparatus for making hollow artificial limbs of plastic sheet fiber, a supporting frame, a rotatable form displaceably mounted in the frame to receive the plastic

sheet fiber, a carriage movable on the frame parallel to the axis of rotation of the form, mechanism for rotating the form and simultaneously propelling the carriage, a spring-pressed roller mounted on the carriage to move radially to the axis of the form to bear on the plastic fiber to deform the material to the contour of the form as the latter rotates and as the carriage moves across the frame, and a band wound without deforming tension on the plastic fiber as the form rotates in advance of the roller to be pressed by said roller to follow the deformation of the fiber to hold the deformed material to the contour of the form until it becomes set.

25 8. In apparatus for making hollow artificial limbs of plastic sheet fiber, a supporting frame, a rotatable form displaceably mounted in the frame to receive the plastic sheet fiber, a plurality of carriages movable on the frame parallel to the axis of rotation of the form, mechanism for rotating the form and simultaneously propelling the carriages across the frame, a spring-pressed roller to follow the deformation of the fiber 80 radially to the axis of the form to bear on the plastic fiber to deform the material to the contour of the form as the latter rotates and as the carriages move across the said roller to follow in deformation of the fiber 85 to hold the deformed material to the contour of the form until it becomes set.

30 9. In apparatus for making hollow artificial limbs of plastic sheet fiber, a supporting frame, a rotatable form displaceably 90 mounted in the frame to receive the plastic sheet fiber, a carriage movable on the frame parallel to the axis of rotation of the form, a spring-pressed roller mounted on the carriage to move radially to the axis of the 95 form to bear on the plastic fiber to deform the material to the contour of the form as the latter rotates and as the carriage moves across the frame, a reel mounted on the carriage, and a band coiled on the reel to be 100 withdrawn from the same and wound without deforming tension on the plastic fiber as the form rotates in advance of the roller to be pressed by said roller to follow the deformation of the fiber to hold the deformed material to the contour of the form until it becomes set.

35 In testimony whereof I have signed this specification.

C. W. THOMAS.
